1,408,745.

Specification of Letters Patent.

Patented Mar. 7, 1922.

Original application filed October 7, 1919, Serial No. 329,100. Divided and this application filed July 29, 1920. Serial No. 399,876.

To all whom it may concern:

Be it known that I, WILLIAM C. KEYWORTH, a citizen of the United States, residing at Paterson, in the county of Passaic and State of New Jersey, have invented certain new and useful Improvements in Swifts, of which the following is a specification.

This application constitutes a division of 10 my application Serial No. 329,100, filed October 7, 1919.

This invention relates to swifts for winding machines, and one part of the invention has to do with the means to impose a drag or 15 resistance to the rotation of the swift under the pull of the thread or yarn, and another part has to do with the means for maintaining the skein properly distended during the rotation of the swift. According 20 to the first part of my invention the usual strap-like device having a pendent weight and made to embrace the hub or other axial part of the swift is eliminated because it is found to act without uniformity, being especially susceptible to change 25 in humidity of the atmosphere, and instead the swift is provided with braking means which is more uniform in action and possesses certain other advantages which will be 30 apparent to those skilled in the art. As to the other part of my invention the object is to provide a swift whose skein supports are movable inwardly toward the hub to permit the application of the skein thereto 35 and when in action are held outwardly to keep the skein distended, and in such manner, moreover, that while the distending effect obtains from start to finish of the unwinding it will be reduced and may be made 40 not excessive toward the finish, when the coils or windings are few and they might otherwise be disrupted. Swifts having inwardly movable skein supports are known, and it is also known to employ springs to 45 hold the skein supports pressed outwardly; in such swifts provision is also made for stops to limit the outward movement of the skein supports, not only to maintain the parts in assembly but to prevent the pressure 50 of the springs, when employed, or centrifugal force, or both, from being active when the last coils or windings, only, re-

main on the swift and breakage thereof would result if the distending action continued. But when this is done the last windings (the remainder of the skein having been paid out) are not distended and therefore not under tension, which is undesirable. According to this invention, the skein support being movable between certain inward 55 and outward limits and adapted to move outward under centrifugal force, means are provided to exert outward pressure thereon which is active (the swift being in rotation) when the support is disposed inward, 60 and inactive when it is disposed outward, of a given position; this means in one practical adaptation of my invention which is herein set forth comprehends an outwardly movable thrust element, as a spoke, and both 65 the force of a spring and centrifugal force to produce said pressure against the skein support, the force of the spring having expended itself (by the spring coming to a 70 state of rest), and the centrifugal force being limited by a stop against which the thrust element comes to bear, when the skein support is outward of the position indicated.

In the accompanying drawing,

Figure 1 is a side elevation of the improved swift;

Figure 2 is an elevation viewing the swift at right angles to its axis, certain parts appearing in section;

Figure 3 is a transverse sectional view on 85 the line 3—3, Figure 2;

Figure 4 shows a detail illustrated in Figures 2 and 3;

Figure 5 is a perspective view of the skein support; and

Figure 6 is a sectional view on the line 90 6—6, Figure 2.

The center part of the swift includes a hub generally designated by the character *a*, and radial tubular sockets *b* having longitudinal 95 slots *c* which form stops *d* at their outer ends. Spokes or equivalent thrust elements are arranged so as to be movable inwardly and outwardly in the sockets, each including a shank *e* and a forked end portion *f* and having a key *g* which limits the outward movement of the spoke by abutting the stop *d*. By means of a spring *h* (Figure 1) which is assumed to be in a state 100

of rest, or fully extended, in said figure, when the spoke is pressed in and then released it will be returned outwardly; this spring is intended primarily to return the 5 spoke to its outward position when it has been pressed inwardly to allow the skein to be adjusted to the swift, and it also coacts with centrifugal force when the skein is first applied to the swift and is therefore so 10 full that it holds the spoke pressed back somewhat. Each skein support is preferably a strip *i* of light material, such as aluminum, serrated on its skein-contact surface and having holes *j* which receive the 15 ends of the fork *f* and having relatively to said fork inward and outward movement limited by the body of the latter and the pins *k*. The entire range of movement of the skein support is from some position 20 more or less inward of that shown at the top of Figure 2, say from the position indicated by the arrow A in said figure, to the position where it abuts the pins *k*, indicated by the arrow C; in the position of the skein support indicated by the arrow B in Figure 2, the position in which it is shown at the top of Figure 2, it will be apparent that with windings on the swift and the swift in rotation neither the force of the spring nor 25 centrifugal force acting on the spoke will be transmitted to the skein support, because the spring is in a state of rest and the spoke is limited against further outward movement by the stop *d*.

30 35 The skein to be applied to the improved swift is formed of such diameter that, though it will hold the spokes pressed back somewhat at the start of the unwinding, being full, toward the end thereof and when 40 the skein becomes thin and danger of breakage thereof is possible, it no longer assumes the outward pressure of the spokes because its effective diameter is then greater than that indicated by the arrow B,—the position 45 of the skein supports where the thrust elements constituted by the spokes cease to be outwardly effective thereon. Thereafter, and as to the remaining or said thin part of the skein, centrifugal force acting on the 50 skein supports, alone, holds them pressed outwardly against the skein, thus preserving it in a state of distention and consequent tension.

55 The skein supports are free to move not only outwardly but inwardly under their own weight, wherein there is a considerable advantage over skein supports outwardly held by springs (of course attended also by centrifugal force when the swift is in rotation) in that the force (centrifugal) impelling the skein supports outwardly when the swift is rotating is constant in character. Moreover, the holes *j* being fairly commodious, each skein support is capable of tilt- 60 ing endwise and sidewise, so that it can ad-

just itself to the skein and will yield to facilitate the release of a winding under-crossed with respect to others. So far as I am aware, movable skein supports in swifts have had their movability confined to rectilineal paths heretofore. 70

The hub *a* includes an enlarged center part *l*, an integral conical boss *m* at one side and an integral shaft *n* at the other side, the hub being preferably formed of wood; 75 there are trunnions *n'* in the boss and shaft, which latter it will be understood keep the swift against axial movement by abutting the bearings for the trunnions. A sleeve *o*, preferably of wood (so as to afford a wood-to-wood contact), having a bore *p* of somewhat greater diameter than the shaft, is fitted over the latter, and its inner end is sheathed in a circular groove *q* in the side of center part *l* so that loose threads cannot 80 interpose themselves between said sleeve and the center part; the sleeve is kept in place by a screw or key *r* engaged in a peripheral groove *s* in the shaft. The sleeve has a radial hole *t* in which is a U-shaped eye *u* carrying the weight *v*, the eye having its free ends bent off in opposite directions so as to support it and being removable (after removing the weight, and the sleeve from the shaft) by pushing it back into the bore of 85 the sleeve. 90

Having thus fully described my invention, what I claim as new and desire to secure by Letters Patent is:—

1. A swift having a skein support and also means to exert a pressure thrust outwardly from the axis of the swift and against the skein support, said means having the extent of its said pressure thrust limited and the skein support being movable inwardly toward, and also outwardly from, said axis and past the limit of said pressure thrust of said means. 100

2. A swift having a skein support, means to exert a pressure thrust outwardly from the axis of the swift and against the skein support, and a stop for said means to limit its said pressure thrust, said skein support being movable inwardly toward, and also outwardly from, said axis and past the limit afforded by said stop. 105

3. A swift having a skein support, means including a spring to exert a pressure thrust outwardly from the axis of the swift and against the skein support, and a stop for said means to limit its said pressure thrust, said skein support being movable inwardly toward, and also outwardly from, said axis and past the limit afforded by said stop. 110

4. A swift having a spoke movable and normally forced outwardly to a given limit when the swift is in rotation, and having a skein support arranged and freely movable outwardly on said spoke. 115

5. A swift having a loose skein support 120

movable inwardly and outwardly therein with equal freedom.

6. A swift having a loose skein support movable inwardly and outwardly therein with equal freedom and capable of tilting therein.

7. A swift having a plurality of outward

projecting portions and a loose skein support connecting said portions and having openings loosely receiving the same and being movable inwardly and outwardly on said spokes with equal freedom.

In testimony whereof I affix my signature.

WILLIAM C. KEYWORTH.
